[57] ABSTRACT

A water heating system has a hot water flow to a radiator branch and a domestic water heating branch. The return lines from these two branches flow to the main return line through a motor operated valve which comprises two coaxial valve seats, and a valve closure for each valve seat. The motor is connected to the closures through a common valve rod. The two closures are between the two valve seats. The main return line connects to the body between the two seats. The branch return lines each connect on the opposite side of a respective valve seat.

CIRCULATING WATER HEATER

BACKGROUND AND SUMMARY OF THE INVENTION

A prior application on which I am a co-inventor, Ser. No. 62,054, filed Aug. 7, 1970, relates to a circulating water heater comprising a water heater, a radiator branch, a branch including a heat exchanger for domestic water, a circulating pump, and a change-over valve by which the water circulation can be changed over from the radiator branch to the heat exchanger branch short-circuiting the radiator branch. In other prior art circulating water heaters the motor operated change-over valve is arranged in the supply flow. However, to avoid the disturbing noise encountered in such heaters at the beginning of domestic water tapping during the closing movement of the valve in a direction of water flow, it has been proposed according to said prior application, that the change-over valve be arranged in the return flow so that the heating circuit and the short-circuit connection are each adapted to be shut off by a closing movement acting against the direction of flow.

In the motor operated valves arranged in the supply flow, as previously mentioned, a distributor piece is provided between the radiator supply line and the radiator return flow (Vaillant Installation and Operating Instructions 1069 A) into the first chamber of which the heating water is supplied from the change-over valve, and is passed on as supply flow heating water from this chamber to the radiators. The heating return flow opens into a second chamber of the distributor piece succeeding the first chamber and separated from the latter by an adjustable short-circuit valve, while the return flow water of the domestic water heater flows into the same chamber, and from this distributor piece there exists a common return flow pipe to the heater. To one side of the previously used change-over valve the supply flow of the heater is connected. On the opposite side of the change-over valve the branch of the supply flow pipe supplying the domestic water heat exchanger is provided, while between the two aforesaid connections a third branch representing the heating supply flow is in communication with the first chamber of the aforesaid distributor piece. On the other side of the change-over valve opposite the distributor piece, the motor controlling the change-over is mounted.

It is an object of this invention, using the arrangement according to said prior application to provide a motor operated three-way valve with distributor piece which may be constructed more simply, manageable and inexpensively.

The solution of this object is achieved by employing a distributor piece (incorporated in well-known manner between the heater supply flow and the heater return flow) having a first valve seat between radiator return flow and heater return flow and a second valve seat, coaxial with the first one, between the heat exchanger return flow and the heater return flow, with the associated valve closures being mounted on a common motor-actuated valve rod and positioned between these valve seats.

An illustrative embodiment of this invention will now be described more fully with reference to the accompanying drawing.

DESCRIPTION OF THE DRAWING

The drawing is a schematic illustration of an embodiment of the invention.

DESCRIPTION OF SPECIFIC EMBODIMENT

The following disclosure is offered for public dissemination in return for the grant of a patent. Although it is detailed to ensure adequacy and aid understanding, 10 this is not intended to prejudice that purpose of a patent which is to cover each new inventive concept therein no matter how others may later disguise it by variations in form or additions or further improvements. The claims at the end hereof are intended as the 15 chief aid toward this purpose, as it is these that meet the requirement of pointing out the parts, improvements, or combinations in which the inventive concepts are found.

20 The heating water from a circulating heater flows from a supply line to the radiator circuit or branch of a room heating system and a domestic water heat exchanger. A distributor 3 is arranged between the supply line 1 and the return to the heater as represented by passageway 2. In the space heating mode of operation, the hot supply water passes through the first chamber 4 of the body of the distributor 3 and the supply connection 5 thereof leading to the radiators (not illustrated). From the radiators this water returns 25 through the return connection 6 and a second chamber 7 of the body of the distributor 3. When valve closure of valve 15 is off its respective valve seat (which it is next to in the drawing), the return water from chamber 7 flows into chamber 16 and thence to passageway 2.

30 35 When domestic water is to be heated by the heat exchanger 10, 11, 12, the hot supply water from line 1 flows into the space 10 between the outer shell 11 and the inner shell 12. Inner shell 12 holds the domestic water to be heated. After heating the heat exchanger, 40 the heating water returns to the circulating heater through chamber 17, chamber 16 and passageway 2. This is permitted by the change-over valve rod 9 assuming the indicated position at which the valve 13 is open by the respective closure being off its seat. The thermostat 14 controls the motor 8 of the change-over valve 9 so that when the domestic water in shell 12 is sufficiently hot the valve rod 9 is returned to the position at which valve 13 is closed and valve 15 is opened. When 45 the temperature of the water in shell 12 is too cool, the thermostat 14 calls for heat and directs motor 8 to position the change-over valve stem 9 in the position illustrated. Motor 9 is mounted on the exterior face of the body of distributor 3. From the common chamber 16 of 50 the distributor the two return flows, which enter chamber 16 through the preceding chamber 7 and the preceding chamber 17, respectively, is passed to the heater through the return passageway 2 and the circulating pump (not illustrated).

55 60 The chambers 4 and 7 are separated from each other by an adjustable short-circuit valve 18 in well-known manner. This valve is used to establish a communication between the supply flow and the return flow of the heating circuit, in case the amount of hot water necessary for the operation of the heater cannot flow through because the resistance of the radiator circuit is too great.

The domestic water heater 12 communicates with the house water supply pipe 19 and has the same pressure. The hot domestic water is drawn from the domestic water heater 12 through the pipe 20.

I claim:

1. In a circulating water heater apparatus comprising a feed water line, a return water line, a radiator branch including a radiator, a flow connection thereto and a return connection therefrom, a domestic water heat exchanger including a flow connection and a return connection, change-over valve means arranged in the return connections so that the flow from the connections to the return line will be shut off by a closing movement acting against the direction of flow, and a motor device for operating the valve means the improvement in said valve means comprising:

a distributor body including said return connections and a passageway for said return line, said body

5

defining two coaxial valve seats, one of which is between the radiator branch return connection and the passageway and the other of which is between the passageway and the heat exchanger return connection, a valve rod extending between the valve seats, two valve closure members affixed to the rod with each being associated with a respective seat, said motor device being operatively connected to said rod.

10 2. In an apparatus as set forth in claim 1, wherein said passageway is between the two valve seats.

3. In an apparatus as set forth in claim 2, wherein said motor device is mounted on the exterior face of the body.

15 4. In an apparatus as set forth in claim 1, wherein said motor device is mounted on the exterior face of the body.

UNITED STATES PATENT OFFICE
CERTIFICATE OF CORRECTION

Patent No. 3,685,733 Dated August 22, 1972

Inventor(s) Frithjof Carouge

It is certified that error appears in the above-identified patent and that said Letters Patent are hereby corrected as shown below:

The name of the Inventor, shown as "Carouge Frithjof", should be --Frithjof Carouge--.

Signed and sealed this 30th day of January 1973.
